(57) **CLAIM**

The ornamental design for a pump lever brake, as shown and described.

DESCRIPTION

FIG. 1 is a perspective view of a pump lever brake showing our new design;

FIG. 2 is another perspective view thereof;

FIG. 3 is another perspective view thereof;

FIG. 4 is another perspective view thereof;

FIG. 5 is another perspective view thereof;

FIG. 6 is side view thereof;

FIG. 7 is a side view thereof, from a side opposite that of FIG. 6.

FIG. 8 is a top view thereof;

FIG. 9 is a bottom view thereof, opposite that of FIG. 8;

FIG. 10 is a rear view thereof; and,

FIG. 11 is a front view thereof.

The broken lines illustrate portions of the pump lever brake and form no part of the claimed design.
